RACK AND FRAME COMBINATION FOR SUPPORTING PAPER STRIPS IN ASCENDING CHROMATOGRAPHY

Horatio Gorman Baikie, 5628 Grove St., Oakland, Calif.

Filed Sept. 15, 1959, Ser. No. 57,557

Term of patent 14 years

(Cl. D16—2)

The figure is a top perspective view of a rack and frame combination for supporting paper strips in ascending chromatography, showing my new design.

I claim:

The ornamental design for a rack and frame combination for supporting paper strips in ascending chromatography, as shown.
